LOUIS M. ASPINWALL, OF WILKINSBURG, PENNSYLVANIA, ASSIGNOR TO WESTINGHOUSE ELECTRIC AND MANUFACTURING COMPANY, A CORPORATION OF PENNSYLVANIA.

ELECTRODE-COOLING SYSTEM.

1,159,884.

Specification of Letters Patent. Patented Nov. 9, 1915.

Application filed January 23, 1915. Serial No. 3,972.

To all whom it may concern:

Be it known that I, LOUIS M. ASPINWALL, a citizen of the United States, and a resident of Wilkinsburg, in the county of Allegheny and State of Pennsylvania, have invented a new and useful Improvement in Electrode-Cooling Systems, of which the following is a specification.

My invention relates to cooling systems for vapor rectifiers and like apparatus, and it has for its object to provide means whereby the temperature of various portions of said apparatus may be maintained at definite predetermined amounts with respect to each other.

The accompanying drawing is a side view, partially in section and partially in elevation, of a mercury-vapor rectifier embodying my invention.

In the operation of vapor rectifiers, especially those of large size belonging to the metal-container type, the amount of heat generated at the anodes is so great as to cause rapid deterioration of the substance thereof, with the expulsion of occluded gases and instability in the operation of the arc. In order, therefore, to maintain the temperature of the anodes within reasonable limits, it has become a usual practice to artificially cool them as, for example, by streams of cooling fluid flowing through the interiors thereof. In an application of Frank Conrad, Serial No. 705,037, filed June 21, 1912, and assigned to the Westinghouse Electric

& Manufacturing Company, there is disclosed a rectifier-cooling system of this type wherein a stream of cooling fluid, after passing through a cathode-cooling space, is divided into branches which flow through

the separate anodes and then reunite. On account of the exceedingly small frictional hydrostatic head developed in each branch of this multiple fluid path, it is difficult to obtain a proper division of cooling fluid between the different branches thereof. The slightest structural dissimilarity between two anodes may give rise to a substantial difference in the relative amounts of cooling fluid passing through them, with consequent erratic and inefficient action of the rectifier.

I have found that, by using a relatively large amount of cooling fluid and passing it through the anode cooling spaces in succession, the anodes may be maintained at substantially equal temperatures. By the

use of a large amount of cooling fluid the temperature increment of the cooling fluid in the first anode may be reduced to any desired figure and thus the difference of the temperature between the two anodes may be brought within any desired limits.

Referring to the accompanying drawing, 2 is the container of a rectifier, preferably of the mercury-vapor-arc type, provided with a liquid cathode 3 and with suitable metallic anodes 4 and 4', preferably of hollow steel. Current is supplied to the anodes 4 and 4' by suitable conductors 5 and flows from the cathode through a suitable conductor 6. The cathode 3 may be maintained in an active condition by any suitable means, such, for example, as a keep-alive circuit shown diagrammatically at 7. The container 2 is surrounded by a jacket 8 of such size that there is provided an annular cooling space 9 around the cathode 3. Suitable tubes 10 and 10' project into the interiors of the hollow anodes 4 and 4' and are open at their lower ends for a purpose to be hereinafter described. Cooling fluid from any suitable source is supplied to the space 9 through a tube 11 and thence flows, via a tube 12, to the interior of the left hand anode 4, through the tube 10 and impinges upon the active heating surface thereof. The cooling fluid then passes through the annular space between the tube 10 and the neck of the anode 4 and through a suitable tube 13 and the tube 10' to the active heating surface of the anode 4'. It is thence conducted through the annular space between the tube 10' and the neck of the anode 4' to a suitable overflow tube 14. Suitable insulating joints 15 are placed in the tubes 12, 13 and 14 in order to prevent short circuiting of the rectifier.

It is essential, in order to obtain satisfactory operation in apparatus of this character, that the cathode be maintained at a relatively low temperature with respect to the anodes, and this result is obtained by my invention because of the fact that the cooling fluid first impinges upon the cathode radiating surface. As hitherto pointed out, the volume of cooling fluid employed should be such that there will be but slight increment in the temperature thereof in the interior of the anode 4. By this means, the cooling fluid supplied to the anode 4' is of substantially the same temperature as that supplied to the anode 4, and the anodes are

maintained at substantially equal temperatures.

While I have described my invention as applied to the two main anodes of a vapor arc rectifier, it is obvious that it may be applied to electrodes of other kinds, such, for example, as keep-alive anodes, either in connection with each other or in connection with the main anodes, and, furthermore, it is readily applicable to other type of apparatus, such, for example, as X-ray tubes.

While I have described and illustrated a preferred embodiment of my invention, I do not desire to be restricted thereto, but desire that only such restrictions shall be placed upon my invention as are set forth in the appended claims or imposed by the prior art.

I claim as my invention:

20 1. In vapor electric apparatus, the combination with a plurality of anodes, each of which is provided with a cooling space, of means for passing a cooling fluid through each of said cooling spaces in succession.

25 2. In vapor electric apparatus, the com-

bination with a plurality of hollow anodes, of means for passing a stream of cooling fluid through the interior of each of said anodes in succession.

3. In vapor electric apparatus, the combination with a cathode and a plurality of anodes, each of said electrodes being provided with a cooling space adjacent thereto, of means for passing a stream of cooling fluid through the cathode-cooling space and then through each of the anode-cooling spaces in succession. 30 35

4. In vapor electric apparatus, the combination with a jacketed cathode and a plurality of hollow anodes, of means for passing a stream of cooling fluid through the cathode-jacket space and then through the interiors of each of the anodes in succession. 40

In testimony whereof, I have hereunto subscribed my name this 18th day of Jan. 45 1915.

LOUIS M. ASPINWALL.
